CLAIM

The ornamental design for a coil handling rack, as shown and described.

DESCRIPTION

FIG. 1 is a perspective view of a coil handling rack showing my new design;

FIG. 2 is a left side elevational view, the right side being a mirror image thereof;

FIG. 3 is a top plan view thereof;

FIG. 4 is a rear elevational view thereof; and

FIG. 5 is a perspective view of another embodiment of the coil handling rack shown in FIG. 1, the opposite side being a mirror image thereof.

FIG. 1

FIG. 2

FIG. 3

FIG. 4

FIG. 5
